Inventor

Harvey E. Lightner

By *John Mulligan* Attorney

UNITED STATES PATENT OFFICE.

HARVEY E. LIGHTNER, OF TECUMSEH, OKLAHOMA.

WRENCH.

1,420,116.

Specification of Letters Patent. Patented June 20, 1922.

Application filed September 21, 1921. Serial No. 502,239.

To all whom it may concern:

Be it known that I, HARVEY E. LIGHTNER, a citizen of the United States, residing at Tecumseh, in the county of Pott and State of 5 Oklahoma, have invented certain new and useful Improvements in a Wrench, of which the following is a specification.

This invention relates to wrenches and more particularly to an improved type of 10 pipe wrench.

The primary object of the invention is to provide a wrench having gripping jaws connected with an operating handle in a manner that will cause the teeth of the jaws to firmly 15 grip the pipe or other rounded member with which the wrench is connected.

The invention has for one of its objects to provide a wrench of this character which will be positive and effective in its operation 20 so that slipping of the jaws on the pipe or other article will not occur.

Other objects of the invention will appear upon consideration of the following detail 25 description and accompanying drawings, wherein:—

Figure 1 is a perspective view of the wrench constructed in accordance with my invention,

Figure 2 is a transverse section taken approximately on the line 2—2 of Fig. 1.

Referring to the drawing by numerals, the wrench handle or bar 1 is provided at one end with a bifurcation 2 forming connecting fingers 3, the terminals of which are 35 provided with openings for receiving a bolt 4. Suspended from the bolt 4 is the primary jaw 5 which consists of two parallel arms 6 having their upper ends provided with openings to receive the bolt 4, the gripping 40 portion 7 being provided with transverse teeth whereby an effective grip may be obtained when the jaw is in use. It will be noted that the portions 6 are laterally spaced apart to provide the space 8 and these suspension arms or portions 6 are provided with 45 openings to receive a pivot bolt 9 upon which the secondary gripping jaw 10 is pivotally mounted. This jaw consists of the gripping portion 11 and the intermediate 50 enlarged portion 12 through which an opening is formed to receive the pivot bolt 9. A rearwardly extending arm or lever 13 is provided with a longitudinal slot 14 for receiving the bight 15 of a link 16 which is 55 pivotally mounted as indicated at 17 on the

arm 1 of the wrench. The link 16 is adapted to slide through the slot 14 in the lever 13 when the parts are swung on their various pivotal points.

In operation, the pipe or other member 60 will be placed between the gripping faces of the jaws whereupon the handle bar 1 will be drawn in a direction to cause the link 16 to exert a pull on the lever 13 thus swinging the lever on the pivot 9 to cause the jaw 11 to 65 move toward the primary jaw 7 for effecting a firm grip on the object with which the wrench is engaged.

Minor changes may be made in the details of construction without departing from the 70 spirit of the invention and the scope of the claims hereunto appended.

What is claimed is:—

1. A wrench of the character described comprising primary and secondary gripping 75 jaws, a handle bar, one end of the handle bar being bifurcated to provide opposite fingers, a bolt supported by the fingers, the primary jaw being provided with suspension arms swung from the said bolt, a pivot member 80 extending transversely across the space between the said suspension arms, the secondary jaw being pivotally mounted on the bolt between the suspension arms, a lever attached to the secondary jaw, and a link carried by the handle bar and slidably engaged with the said lever whereby swinging movement of the lever will occur when the handle bar is swung on the uppermost pivot bolt.

2. A wrench of the character described 90 comprising an elongated handle bar having one end bifurcated to provide opposite supporting fingers, a transverse supporting bolt carried by the terminals of the fingers, a primary jaw, suspension arms laterally 95 spaced apart and hung from the said supporting bolt, a secondary jaw provided at its intermediate portion with an opening, a pivot bolt carried by the suspension arms and extended through the opening in the 100 secondary jaw, a lever attached rigidly to the said secondary jaw and provided with a longitudinal slot, and a link pivotally suspended from the handle bar of the wrench and engaged with the lever through the said 105 slot, whereby swinging movement of the lever will cause the link to move the said jaws toward each other.

In testimony whereof I affix my signature.
HARVEY E. LIGHTNER.
